CLOTHES HANGER

Martin Lowe, New York, N. Y., assignor of one-half to Abraham Block, New York, N. Y.

Application November 10, 1945, Serial No. 627,909

2 Claims. (Cl. 223—94)

1

This invention relates to new and useful improvements in clothes hangers.

The invention refers to a clothes hanger which may fold so that it may be easily applied to dresses and other garments having small neck openings. This construction makes it unnecessary to engage the hanger through the bottom of the dress to the neck opening for supporting it.

The invention has particular reference to a novel construction which makes it exceptionally simple to fold or collapse the hanger when desired, and to move the parts back to original extended positions.

It is proposed to characterize the new clothes hangers by a pair of shoulder pieces which are hingedly connected together and which have abutting elements for limiting pivoting from a horizontal position upwards. It is proposed to provide each shoulder piece with a handle that projects upwards from points close to the hinge. One of said handles is provided with a top hook by which the hanger may be supported on a rod, nail or other supporting element. It is proposed to provide the other handle with a hook capable of releasably engaging the last mentioned handle for releasably holding the shoulder pieces in their horizontal position.

An important feature of the invention resides in the fact that one of the shoulder pieces is directly connected with the hook that supports the hanger and the other shoulder piece is provided with a handle by which it may be pivoted from horizontal positions downwards and which is provided with a hook capable of snapping on and against the other handle and by which the shoulder pieces are held in their horizontal position.

The broad concepts of this invention may be applied to numerous forms, two of which are disclosed in this specification. In one of the forms, the shoulder pieces includes rods of wood, metal, or other material, or thermo-plastic rods which not only are decorative but which are desirable material for the shoulder pieces. In the second form, the entire hanger is formed from two lengths of wire which are hingedly connected with a rivet, or bolt.

The invention also proposes to so construct the shoulder pieces that they are capable of receiving and holding shoulder straps of garments to pre-

2

vent the garments from slipping off of the hanger, or to receive loops of garments for supporting them.

Still further the invention proposes the construction of new and improved clothes hangers, as briefly explained which are exceptionally simple in construction and durable and which can be manufactured and sold at a reasonable cost.

10 For further comprehension of the invention, and of the objects and advantages thereof, reference will be had to the following description and accompanying drawings, and to the appended claims in which the various novel features 15 of the invention are more particularly set forth.

In the accompanying drawings forming a material part of this disclosure:

Fig. 1 is an elevational view of a clothes hanger constructed in accordance with this invention.

20 Fig. 2 is a fragmentary enlarged horizontal sectional view taken on the line 2—2 of Fig. 1.

Fig. 3 is a fragmentary enlarged horizontal sectional view taken on the line 3—3 of Fig. 1.

Fig. 4 is an enlarged vertical sectional view 25 taken on the line 4—4 of Fig. 1.

Fig. 5 is an elevational view of another clothes hanger embodying this invention.

Fig. 6 is a fragmentary horizontal sectional view taken on the line 6—6 of Fig. 5.

30 Fig. 7 is a fragmentary horizontal sectional view taken on the line 7—7 of Fig. 5.

The clothes hanger, as illustrated in that form of the invention shown in Figs. 1 to 4 inclusive, includes a pair of shoulder pieces 10 and 11 which are hingedly connected with a pintle rivet 12'; or other hinge connection, and which are provided with abutting elements, or surfaces 12 and 13 for limiting pivoting from a horizontal position upwards. The shoulder piece 10 comprises a metal inner end section 14 and a thermo-plastic or other suitable material outer end section 15. The metal section 14 is formed with an opening 16 into which the end of the thermo-plastic material section 15 is engaged and cemented. The shoulder piece 11 is formed from a metal inner end section 17 and an outer thermo-plastic material end section 18. The metal section 17 is formed with an opening 19 into which the end of the thermo-plastic material section 18 is engaged and cemented. The adjacent ends of the

metal sections 14 and 17 are formed with inter-engaging portions 20 and 21 through which the pintle rivet 12' passes and by which the shoulder pieces 10 and 11 are hingedly connected. The abutting elements 12 and 13 comprise adjacent abutting shoulders on the hinge construction.

Handles 23 and 24 project upwards from each of the shoulder pieces 10 and 11, from points close to the hinge rivet 12'. The handle 23 continues at the top into a top hook 25 by which the hanger may be supported on a rod or other support element. The handle 24 is formed with a laterally extending top portion 26 which terminates in a hook 27 releasably engaging the handle 23 for releasably holding the shoulder pieces 10 and 11 in their horizontal position. Preferably the handles 23 and 24 are constructed from wire, or other resilient material. The parts are so designed that when the abutting elements 12 and 13 engage each other limiting further upward pivoting of the shoulder pieces 10 and 11, then the hook 27 is adapted to be engaged with the handle 23. This construction holds the shoulder pieces 10 and 11 from being loose.

The outer sections 15 and 18 of the shoulder pieces 10 and 11 are preferably made from thermo-plastic rods. The outer ends of these thermo-plastic rods are formed with inclined slits 29 extended inwards from their top portions into which the shoulder straps of a garment may be engaged to prevent it from slipping off of the hanger.

The operation of the clothes hanger may be understood from the following:

In Fig. 1 the clothes hanger is shown in a position in which the shoulder pieces 10 and 11 are extended in their horizontal position. The hanger may be supported on a support rod, or other element. When it is desired to place a garment on the hanger, particularly one having a small neck opening, it is a simple matter to flex the top portion 26 of the handle 24 backwards so as to force the hook 27 off of the handle 23 and then the shoulder piece 11 may be lowered to any extent by holding on to the handle 24 and allowing the shoulder piece 11 to move downwards, as for example illustrated by the dot and dash lines in Fig. 1. In this way the hanger may be engaged into a small neck opening. Then the handle 24 may be pivoted back towards the handle 23 and the hook 27 may be snapped about the handle 23 when the shoulder pieces are extended in the horizontal position. With a little practice the handles 23 and 24 may be manipulated with one hand, while the hanger is being supported with said one hand, for engaging or disengaging the hook 27 on the handle 23, for lowering or raising the shoulder piece 11 as required.

In Figs. 5 to 7 another embodiment of the invention has been disclosed which in principle is identical to the prior form. In construction, it is somewhat different. This clothes hanger includes a pair of shoulder pieces 30 and 31 hingedly connected together with a pintle rivet 32 and having abutting elements 33 and 34 for limiting pivoting from a horizontal position upwards. A handle portion 35 projects upwards from the shoulder piece 30 near its hinge point. A handle 36 projects upwards from the shoulder piece 31 from near its hinge point. The handle 35 continues at the top into a hook portion 37 by which the hanger may be supported on a rod, nail, or other supporting element. The handle 36 continues into a horizontal portion 38 which termi-

nates in a hook 39 releasably engaging the handle 35 for releasably holding the shoulder pieces 30 and 31 in their horizontal position.

The shoulder piece 31 and the handle 36 are formed from one length of wire. Similarly the shoulder piece 30 and the handle 35 are formed from one length of wire. The hinge of said shoulder pieces are formed by turning portions of these lengths of wires into loop portions 40 and 41 respectively for the pintle rivet 32. The loop portions are flattened so as to form the abutting elements 33 and 34. These abutting elements 33 and 34 are in the nature of shoulder portions engaging each other when the shoulder pieces 30 and 31 are in their horizontal position. The shoulder pieces 30 and 31 may pivot downwards.

The outer ends of the shoulder pieces 30 and 31 are formed with inturned sections 42 terminating in upwardly directed portions 43 forming supports for the shoulder straps of garments.

The operation of this form of the invention is substantially identical to the prior form. With one hand it is possible to snap off the hook 39 from the handle 35 and with the same hand it is possible to move the handle 36 so as to lower and raise the shoulder piece 31 as schematically indicated by the dot and dash lines in Fig. 5.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a clothes hanger, a pair of substantially horizontal shoulder pieces hingedly connected together and adapted to pivot from downwardly extended positions upwards to said substantially horizontal position, said shoulder pieces having abutting elements for limiting pivoting from said substantially horizontal position upwards, a handle projecting upwards from each of said shoulder pieces at points close to their hinge, a hook on one of said handles extending towards and partially around the other handle, said handles being disposed in a plane substantially at right angles to the axis of the hinge connection of said shoulder pieces whereby with the thumb and one finger of one's hand engaging the outer sides of said handles the shoulder pieces may be held in said substantially horizontal position with said abutting elements abutting each other, and said handles may be slightly flexed together and slightly laterally for disengaging said hook and then said shoulder pieces may be lowered by allowing said handles to move apart.

2. In a clothes hanger, a pair of substantially horizontal shoulder pieces hingedly connected together and adapted to pivot from downwardly extended positions upwards to said substantially horizontal position, said shoulder pieces having abutting elements for limiting pivoting from said substantially horizontal position upwards, a handle projecting upwards from each of said shoulder pieces at points close to their hinge, a hook on one of said handles extending towards and partially around the other handle, said handles being disposed in a plane substantially at right angles to the axis of the hinge connection of said shoulder pieces whereby with the thumb and one finger of one's hand engaging the outer sides of said handles the shoulder pieces may be

held in said substantially horizontal position with said abutting elements abutting each other and said handles may be slightly flexed together and slightly laterally for disengaging said hook and then said shoulder pieces may be lowered by allowing said handles to move apart, said shoulder pieces being of wire material, a pintle for hingedly connecting said shoulder pieces, and said wire material being flattened in the vicinity of said pintle and said flattened areas being formed with said abutting elements.
